(57) **CLAIM**

The ornamental design for a communications terminal display panel with graphical user interface, as shown and described.

DESCRIPTION

FIG. 1 is a front view of a communications terminal display panel with graphical user interface, showing my new design; and,

FIG. 2 is a front view of the communications terminal display panel with graphical user interface in accordance with a second embodiment.

The outermost broken lines illustrate a display panel or portion thereof and form no part of the claimed design. The
